(57) **CLAIM**

The ornamental design of an accessory bracket, as shown and described.

DESCRIPTION

FIG. 1 is a left side elevational view of the accessory bracket of the present invention, the right side being a mirror image thereof;

FIG. 2 is a front elevational view thereof;

FIG. 3 is a rear elevational view thereof;

FIG. 4 is a top plan view thereof;

FIG. 5 is a bottom plan view thereof.

The broken lines shown in FIG. 1 of the drawing are for illustrative purposes only and form no part of the claimed design.
